UNITED STATES PATENT OFFICE.

EDWARD J. SHUR, OF NEW ORLEANS, LOUISIANA.

INNER DOOR FOR CARS.

1,305,838.

Specification of Letters Patent. Patented June 3, 1919.

Application filed November 11, 1916. Serial No 130,814.

To all whom it may concern:

Be it known that I, EDWARD J. SHUR, a citizen of the United States, residing at New Orleans, in the parish of Orleans and State 5 of Louisiana, have invented new and useful Improvements in Inner Doors for Cars, of which the following is a specification.

My present invention pertains to cars, more particularly refrigerator cars of the 10 kind disclosed in my contemporary application filed Sept. 18, 1915, Serial Number 51,425.

The object of my present invention is the provision of an overhead, slideable open-work door, calculated in its operative position to protect bananas against mutilation or theft when the ordinary outer door of the car is open and at the same time afford ample ventilation.

20 The invention will be fully understood from the following description and claim, when the same are read in connection with the drawings, accompanying and forming part of this specification, in which:

25 Figure 1 is a longitudinal vertical section showing my novel inner door as closed.

Fig. 2 is a transverse section of the same.

Fig. 3 is a similar view with the door in its raised, idle position.

30 Fig. 4 is an enlarged detail view showing disconnected portions of the door sections.

Fig. 5 is a detailed section, on an enlarged scale, showing the connection between one end of a door slat and the adjacent guide 35 member.

Similar numerals of reference designate corresponding parts in all of the views of the drawings.

The car body 1 is provided, by preference, 40 with a false, open-work floor 2, and is also provided with conventional door openings 3, only one of which is illustrated. I would have it understood here that any suitable outside door may be employed to control the 45 opening 3, but inasmuch as said outside door forms no part of my invention, I have deemed it unnecessary to illustrate the same.

In furtherance of my invention, I provide 50 at opposite sides of the opening 3 guide members 4, which are of circular form in cross-section and are slotted throughout their length, as indicated by 5. The said guide members are fixed in the body 1, and comprise vertical portions 6 adjacent to the opening 3, intermediate curvilinear portions 55 7 above the opening 3, and upper substan-

tially horizontal portions 8, which extend to points adjacent to the longitudinal median line of the car roof, as shown in Figs. 2 and 3.

60 My inner door is preferably, though not necessarily, formed in two sections, the upper section being provided with a hasp 9, and the lower section with a staple 10, through the medium of which the sections 65 may be connected together so as to be susceptible of movement as a unit when the same is deemed expedient. It will be manifest from the foregoing that when desired the lower section, numbered 11 in Fig. 4, 70 may be left in its lowermost position, while the upper section, numbered 12, may be moved to the position shown in Fig. 3, in which it will remain of itself. Thus, when desired, the lower portion of the opening 3 75 may be barred while the upper portion may be left free. Each of the sections 11 and 12, comprises spaced slats 13, hinges 14 connecting the slats 13 and having their pintles arranged in the spaces between the slats, Fig. 80 2, and protective members in the form of bifurcated plates 15 straddling and fixed to the ends of the slats, Fig. 5, and provided at their outer ends with projections 16 which are flat in form as will be seen by comparison of Figs. 4 and 5. The said projections 16 of the slats are disposed in the guide members 4, and hence it will be manifest that the inner door may be expeditiously and 85 easily moved from the position shown in Fig. 2 to that shown in Fig. 3 and vice versa.

90 For the purpose of maintaining the door in its idle raised position, I provide the hook 17. The said hook 17 is hinged at 18 to lugs on one guide member 4 and is designed to be positioned as shown in Fig. 3 after the slatted door is raised to the full extent. Manifestly, when it is desired to place the door in its working position, it is simply necessary to swing the hook support inwardly and out of engagement with the lowermost slat, when the door may be moved to the position shown in Figs. 1 and 2.

100 The slats 13 are preferably of wood, and when made of said material they will last 105 for an indefinite period inasmuch as the only parts subjected to wear are the hinges 14, the plates 15 and the guide members 4. It will also be manifest that the plates 15 effectually guard the ends of the slats and 110 preclude frictional wear of the same against the members 4.

It will be gathered from the foregoing that my novel inner door is simple and inexpensive in construction, and is calculated to constitute a valuable adjunct to a car for shipping bananas and other fruit.

Having described my invention, what I claim and desire to secure by Letters Patent, is:

The combination of a body having a door opening, vertically-disposed guide members fixed to the body, at opposite sides of said opening, and an inner, vertically-slidable door comprising spaced, horizontally-disposed and vertically movable slats having their ends disposed and movable in the guide

members, and hinges interposed between and connecting the spaced slats and having opposed members and pintles; the said opposed members and the pintles being disposed between the slats to effect the flexible connection thereof, and maintain the slats in spaced relation to afford ventilation. 20

In testimony whereof I have hereunto set my hand in presence of two subscribing witnesses.

EDWARD J. SHUR.

Witnesses:

R. G. EUSTIS,
M. E. KNIGHT.
